UNITED STATES PATENT OFFICE.

JOSEPH O. BEAZLEY AND ISAAC L. MORRIS, OF BALTIMORE, MARYLAND.

COMBINED FRUIT PARER AND SEEDER.

SPECIFICATION forming part of Letters Patent No. 295,476, dated March 18, 1884.

Application filed January 9, 1884. (Model.)

To all whom it may concern:

Be it known that we, JOSEPH O. BEAZLEY and ISAAC L. MORRIS, citizens of the United States, residing at Baltimore, in the county of Baltimore and State of Maryland, have invented certain new and useful Improvements in Fruit Parers and Seeders Combined, of which the following is a specification, reference being had therein to the accompanying drawings.

This invention relates to improvements in machines for paring, seeding, and splitting peaches and other fruit by one operation of the machine, all of which will be hereinafter more particularly described, and pointed out in the claims.

In the drawings forming part of this specification, Figure 1 is a plan view of the machine. Fig. 2 is a side elevation of the machine. Fig. 3 is an enlarged section of the parts which hold the fruit, and by which it is rotated against the paring-knife. Fig. 4 is a side view of the pinion. Fig. 5 is an end view of the gage-plates, as shown edgewise in Fig. 25 3 at Q Q. Fig. 6 represents the details of the seeding-knives and springs. Fig. 7 shows the paring-knife and gage; Fig. 8, details of the splitting-knife frame.

A is a metal plate having arms A', A'', and 30 A''', all of which constitute the frame for sustaining the various parts of the machine. This plate A has a web, B, on the back, which may be made solid or ornamented with open-work, as represented in Fig. 1. In this web are two holes, b b, which are fitted to the two standards b' b', attached to a thwart-piece, b''. These standards have each a clamp at the lower end, and screw b''', by which the machine can be attached to the edge of a table, C. The 40 machine can be fastened in any other manner.

D is a wheel having a cam, d, on its periphery, secured to the plate A by a hub, d', on a short shaft in a boss, a.

Attached to the plate A and around the 45 boss a is a curved and warped-surface cam, a', for a purpose which will be hereinafter explained.

On the front side of wheel D, and pivoted in ears d'' d'', is the paring-knife stock or arm 50 E, around whose shaft e is coiled a spring, e'. Extending from the shaft e is a long finger, e''.

The knife-arm E carries a sickle-edged knife,

F, and its gage-bar f. (Both shown enlarged in Fig. 7, where the serrated surface of the knife F is shown.)

On the back of wheel D are beveled teeth to match the pinion D', as seen in Fig. 1. There is also on the back of wheel D a pin, d'', (shown in Fig. 2,) and also on the front side a pin, d'''. The purposes of these will be hereinafter explained.

Pivoted to the lowest part of plate A, immediately below wheel D, as seen in Fig. 2, is a bent lever, G, to the long arm of which is connected a rod, G'. The other end of rod 65 G' is pivoted to a pendant, H, secured to the inner end of the adjustable arm I, which is fastened on the knife-rod J by a set-screw, i, which rod J is fitted to slide freely in the two arms A'' A''' of the plate A.

Attached to the end of rod J is a knife-frame, K, consisting of the back bar, k, which is composed of upper and lower plates inclosing a back-spring, k'.

K' K' are two bars pivoted at k'' k'' to the 75 back bar, with their ends against the back-spring, which keeps them in the position as shown in Fig. 2. On the end of these bars K' are blades k''', for splitting the fruit.

L are two thin spring-steel knife-blades, 80 which are slightly curved near the middle in opposite directions, as shown in Fig. 6. The ends of these blades L L pass through slots in the knife-bars K'', and project far enough beyond them to receive the ends of bifurcated 85 springs l l, and one end of these blades, l', is turned up outside of the spring l, as seen in Fig. 6, and at the other end the spring l is retained by a pin, l''.

On the top and bottom of knife-bar K'' are 90 springs m m, Fig. 6, which impinge on the spring knife-blades L L, to keep these blades close together where they curve in opposite directions, but permit them to spread as they pass around a peach-stone, and are held closely 95 to the stone to cut the fruit very near it. The yielding action of the spring-blades L L in opening is controlled also by the end springs, l l.

On shaft J is the adjustable arm I, secured 100 by the set-screw i. The arm I clasps plate A and slides upon it.

Attached by a pivot to the arm I at plate A is a connecting-bar, M, which extends to the

wheel D, and at its free end is a notch, *n*, which is engaged by the pin *d'''* on the back of wheel D, and as the wheel is carried around in the direction of the arrows the pin *d'''* carries the bar M with it, and also rod J, with the knife-frame, is carried to the fruit, which has been placed on the points or tines *t t*. When the wheel D has passed around with the bar M until it is arrested by the hub of the wheel, the pin *d'''* is carried out of the notch in the bar M, and immediately thereafter the pin *d'''* on the face of wheel D arrives at the lever G, and moves it so that its long arm shoves to the rear the connecting-bar G', which carries backward the pendant H and arm I, rod J, and knife-frame K, and at the same time the fruit is pulled from the tines and drops into a receptacle below, and the tines are free for another fruit, which is immediately put on.

At the outer end of the arm A' is secured in proper bearings, and having its center in exact line with the center of the rod J, the apparatus for holding and turning the fruit to be pared and cored and split.

N is a spur-wheel secured to a short shaft, N', which passes through plate A in suitable bearings, and on the inner end of which is the beveled pinion D'. Wheel N is operated by handle *n'*, and gives motion to the whole apparatus.

O is a pinion-wheel geared with wheel N, and loosely mounted on a shaft, P, having a feather, *p*, and on which wheel O slides freely to be geared with or detached from the wheel N. The details of this shaft and its connections are shown in section in Figs. 3 and 4, enlarged. The hub of the pinion-wheel O is formed into a collar, *o'*, and in its inner face is a hole, *o''*, Fig. 4, to receive a pin, *r*, which projects from the face of the arm A', and when the pinion O is unshipped the pin *r* enters the hole *o''* and keeps pinion O from revolving. The shaft P has in it a neck, *p'*, and a screw, *r'*, through the side of the hollow cylinder R keeps the shaft P in place laterally, but permits it to revolve.

At the inner end of shaft P there is a screw-threaded socket to receive the end P' of the fruit-holder, which is threaded, and on which is a nut, *p''*, to regulate the length.

Attached to P' are four tines, *t t*, for holding the fruit.

P'' is a gage to stop the end of the kernel of the fruit when the coring-knives force it forward.

Q Q are gages to stop the pieces of the fruit when the splitting-knives force it forward. These gages Q are held by rods *q q*, which are guided through holes in the ears *r'' r''* on the cylinder R, and their ends are riveted to the branches of a yoke, *s*, on the long arm of a lever, S, which is pivoted to the side of arm A', Fig. 1. The short arm of lever S is pivoted to a short rod, R', which passes through the arm A' and the brace-bar inside of it, so that the end of rod R' impinges on the pe-

riphery of the cam *d* on wheel D. Rod R' has coiled around it a spring to keep it in constant contact with the periphery of the wheel D. When the wheel D is revolved until the cam *d* arrives at rod R', the cam will force the rod outwardly, and the long arm of lever S throws the pinion O out of gear from spur-wheel N, and it is held fast by the pin *r*, and the fruit-holding apparatus is held stationary, and at this time the knives are brought forward into action by the pin *d'''*, carrying the rod M, which moves arm I, rod J, and the knife-frame. The kernel is cut out, and the fruit is split open, the same having been peeled previously by the paring-knife. When the wheel D was in motion before the pinion O was disengaged, the spur N caused the pinion O to revolve very rapidly, and consequently the fruit on the tines *t t* was revolved correspondingly. The position of the paring-knife stock E on wheel D is so regulated that when the pinion O and the fruit are being revolved the knife F, which starts at the point of the fruit, moves slowly from the point to the butt. At the same time the knife F is kept in contact with the fruit, and it is nicely pared. The point *e'* of the knife-stock, which has passed over the cam *a'*, drops down from the cam *a'* at the offset *e'''*, Fig. 1, and the spring *e* causes the knife F to drop below the holding apparatus and pass under it as the wheel D continues to revolve, and so soon as the finger-point *e''* reaches the other end of cam *a'* the knife F is again thrown by the cam *a'* into the position at the point of the fruit to pare the next one, which has in the meantime been placed on the tines. When the wheel D revolves and brings the cam *d* around so that the offset reaches rod R', the rod is forced over the offset, and the lever S is thrown in and the pinion O is thrown into gear with spur-wheel N just as the knife F is in position for paring and the fruit commences revolving toward it.

Having experimented very extensively with various forms of paring-knives, we find none that can operate so successfully as the sickle-edged blade which is represented in Fig. 7.

F is the inside surface of the blade, cut into long inclined serrations. The other side is beveled from a thick edge, to give a sharp edge where the serrations form the fine teeth of a saw. The gage-bar *f* is adjusted far enough from the serrated side of the blade F to permit the parings to pass out and to gage the thickness. The two are secured to the knife-stock E by a screw.

We are aware that our devices for splitting and coring are not new by themselves; but we do not know of any machine in which these have been used in connection with a device for paring the "fruit."

We claim—

1. A machine, as herein described, having a paring-knife, double-splitting-knives, to pass each side of the kernel of the fruit, and two elastic coring-blades for removing the kernel,

all combined and operated substantially as and for the purpose described.

2. The combination of the driving mechanism, the wheel D, with its cam-rim d, the pin 5 d'', sliding bar M, arm I, rod J, carrying the splitting and coring knives, the levers G G', and arm H, substantially as and for the purpose described.

3. The wheel D, with cam-rim d, rod R', lever S, with its yoke s, and sleeve and pinion O, having the hole o'' in its inner face, in combination with the pin r in the side of the arm A', all substantially as and for the purpose described.

15 4. The splitting-knives k'', pivoted to the back bar, k, having the spring k', in combination with the bifurcated end springs, l l, and the spring-blades L L, all substantially as and for the purpose described.

20 5. The spring coring-blades L L, curved as described, in combination with the bifurcated

end springs, l l, and the binding-springs m m, and the bars K'' of the splitting-knives k'', and the back bar, k', all substantially as and for the purpose described.

25 6. The combination of the spur-wheel N, pinion O, shaft P, and fruit-holder P', having an adjustable screw and nut, and times for holding the fruit, and gage P'' for the stone, and gages Q Q for the fruit, substantially as 30 described.

7. The paring-knife F, having one side and the sharp edge cut into sickle-teeth, substantially as and for the purpose described.

In testimony whereof we have affixed our signatures in presence of two witnesses.

JOSEPH O. BEAZLEY.
ISAAC L. MORRIS.
